UNITED STATES PATENT OFFICE

AMOS SEYMOUR, OF WESTERLY, RHODE ISLAND, ASSIGNOR TO DRAPER CORPORATION,
OF HOPEDALE, MASSACHUSETTS, A CORPORATION OF MAINE

HARNESS CONNECTER FOR LOOMS

Application filed September 8, 1930. Serial No. 480,430.

This invention relates to harness connecters for looms. In a loom each harness frame is usually operated by connecters secured at one end to the harness frame, extending around sheaves on the loom frame and then connected to a suitable actuating element, such, for example, as a cam-operated lever or the jack of a dobby. These connecters must be flexible, at least in the portion extending around the 10 sheave, and they must be adjustable as to their length in order to secure the proper operation of the harness frame in the formation of the shed and to provide for such changes as may be necessary due to changes 15 in the weave, wear of the parts, or adjustment of the actuating mechanism.

The object of the present invention is to provide a simple and practical form of such a harness-frame connecter in which the connecter is made in two or more parts and in which these parts may be longitudinally adjusted with respect to each other so as to adjust the length of the connecter and in which this adjustment may be made without 25 longitudinal shift of the parts taking place during the adjustment.

In adjusting the length of such connecters it is usually very difficult to stretch them or to draw the parts longitudinally together beyond the point required by the adjustment being made. The present invention enables this adjustment to be made in a simple and effective manner without experiencing this difficulty.

35 In the drawings:

Fig. 1 is a somewhat diagrammatic front elevation partially broken away of a portion of a loom frame, a harness frame, a dobby having a jack or harness-frame actuator, and 40 a preferred form of harness-frame connecters embodying the present invention.

Fig. 2 is a view partially in longitudinal cross-section and partially broken away of one of the harness-frame connecters shown in 45 Fig. 1.

Fig. 3 is a top plan view of the construction shown in Fig. 2.

Fig. 4 is a detail showing the latching element of the device in position as it is being 50 threaded through aligned apertures of the

parts of the connecter when an adjustment is required.

As illustrating one use of the invention, a portion of a loom frame is shown having the arch 1 provided with the rotatable sheaves 2, 55 a harness frame 3 beneath the arch, and a portion of a dobby mechanism 4 secured to the arch. A jack 5 forming a part of the dobby is illustrated, and this jack serves as an illustration broadly of a harness-frame 60 actuator movable transversely of the loom to effect the raising and lowering of the harness frame, as required in the weaving operation. Usually two harness-frame connecters are employed, as illustrated, extending 65 from suitable attaching devices, such as the hooks 6, on the harness frame over the sheaves 2 to the jack or actuator 5.

In the preferred form of this invention, a portion of the conencter is formed as a flexible element 7, herein shown as a cord of suitable construction having at its ends eyes 8. One of these eyes 8 enables this flexible element to be connected to the harness frame, as by being hooked over the hooks 6. From the harness frame this flexible element extends up and around the proper sheave 2, and is provided with a terminal extension 9 herein shown as a strap, which may be of leather or other suitable material and which at one end is hooked into the eye 8. Another portion of the connecter is formed as a rod 10, preferably made of wire and adapted for connection at one end to the harness-frame actuator. 75 For this purpose it is shown as formed with 80 a hook 11 to engage a wire loop 12 on the jack or actuator 5.

The end of the rod 10 opposite the hooked end 11 and the free end of the terminal extension 9 have apertures therethrough, and at least one of these elements has a plurality of such apertures extending longitudinally thereof. In the construction illustrated, a single aperture is formed in the end of the 95 rod 10 by bending it into an eye 13, while in the terminal extension 9 a plurality of apertures 14 are punched therethrough.

It will thus be seen that by shifting the apertures in the rod 10 and terminal exten- 100

sion 9 into different positions the length of the connector may be varied.

A third feature of the invention resides in a latching element threadable through the aligned apertures of the rod 10 and terminal extension 9 without substantial longitudinal shifting of said rod and extension and having means whereby it may be locked in threaded position. This latching element is preferably formed of wire and comprises a shank 15 having at one end a hook 16 extending in a plane at right angles to the shank and so arranged that when the shank of the latch is parallel with the connector this hook may be caught around the rod 10 and thus engage the rod. The shank 15 of the latch, at the other end, is provided with an arm 17 also extending at right angles to the shank and adapted, as shown in Fig. 2, to extend through aligned apertures of the rod 10 and terminal extension 9. This arm 17 terminates in an angularly-disposed threading and locking portion 18.

The operation of the device will be clear from the drawings. Assuming, for example, that the connector is to be drawn up tight, the latch is removed and the two parts of the connector are pulled together until they reach the required position and an aperture in the rod 10 is in alignment with an aperture in the extension 9. The threading portion 18 of the latch is then threaded into the aligned apertures, as shown in Fig. 4, and then the latch is swung into the position shown in Fig. 2, bringing the arm 17 of the latch through the aligned apertures. The hook 16 is then engaged with the rod 10, and the portion 18 moves into the position shown in Fig. 2, and thus the latch is locked and held in locking position. It will be observed that as the latch is being threaded through the aligned apertures no substantial longitudinal shift of the parts of the connector takes place, and thus the adjustment of the connector may be made under the most difficult conditions.

Having thus described the invention, what is claimed as new, and desired to be secured by Letters Patent, is:

1. A harness connector for a loom having a harness actuator, a harness sheave and a harness frame comprising a flexible element for connection to the harness frame and for extending therefrom around the sheave, a terminal extension of the flexible element, a rod for connection at one end to the harness actuator, the opposite end of the rod and the terminal extension having apertures therethrough, and at least one of the said elements having a plurality of apertures longitudinally thereof, and a latch having a shank with a hook at one end to engage the rod when the shank is parallel therewith and at the other end an arm at right angles to the shank adapted to extend through aligned apertures of the rod and terminal extension and terminating

in an angularly-disposed threading and locking portion.

2. A harness connector for a loom having a harness actuator, a harness sheave and a harness frame comprising a flexible element for connection to the harness frame and for extending therefrom around the sheave, a terminal extension of the flexible element, a rod for connection at one end to the harness actuator, the opposite end of the rod and the terminal extension having apertures therethrough, and at least one of the said elements having a plurality of apertures longitudinally thereof, and a latching element threadable through aligned apertures of the rod and terminal extension without substantial longitudinal shifting of said rod and extension and provided with means for locking it in threaded position.

3. A harness connector for a loom having a harness actuator, a harness sheave and a harness frame comprising a flexible element for connection to the harness frame and for extending therefrom around the sheave, a terminal extension of the flexible element, a rod for connection at one end to the harness actuator, the opposite end of the rod and the terminal extension having apertures therethrough, and at least one of the said elements having a plurality of apertures longitudinally thereof, and a wire latch presenting a shank having a hook at one end extending in a plane at right angles to the shank to engage the rod when the shank is parallel therewith and having at the other end an arm at right angles to the shank adapted to extend through aligned apertures of the rod and terminal extension and terminating in an angularly-disposed threading and locking portion.

In testimony whereof, I have signed my name to this specification.

AMOS SEYMOUR.
